UNITED STATES PATENT OFFICE.

FRANK B. ZIEG, OF FREDERICKTOWN, OHIO, ASSIGNOR, BY MESNE ASSIGNMENTS, TO THE F. B. ZIEG MFG. COMPANY, OF FREDERICKTOWN, OHIO, A CORPORATION OF OHIO.

WRINGER.

Application filed May 25, 1921. Serial No. 472,361.

To all whom it may concern:

Be it known that I, FRANK B. ZIEG, a citizen of the United States, residing at Fredericktown, in the county of Knox and 5 State of Ohio, have invented certain new and useful Improvements in Wringers, of which the following is a specification.

The invention relates to clothes wringers and more particularly to power driven 10 wringers used in connection with washing machines. The invention has special relation to a safety device for the quick release and separation of the rollers in case of emergency.

15 A danger inherent in the ordinary type of power driven wringers is the liability of injury to the operator by having a hand caught between the compression roll in feeding the clothes through the wringers. 20 Serious injury may thus occur before the driving mechanism can be disconnected. Similarly, the wringer mechanism may be broken by bunching of clothes in too great thickness to pass between the rollers. These 25 conditions have necessitated the development of means for quickly releasing the compression between the rollers and for permitting their separation sufficiently for the withdrawal of a hand or clothing caught 30 therebetween.

In the safety devices heretofore used, certain disadvantages of construction and uncertainties of operation have been present 35 which I have overcome in my present invention.

One of the objects of my invention is to provide a quick operating roller releasing device which also operates to positively separate the rollers when released.

40 Another object of the invention is to provide means for controlling the device which is conspicuously available to the operator in any position which the latter may be.

Another object is to provide a releasing 45 device in which a unitary control is operable in one direction to release the rollers from tension and widely separate them, and by a reverse movement of the control to restore the rollers to operative position under 50 tension as before.

A further object is to provide a safety device in which is incorporated means for tensioning the rollers and so constructed 55 that the operation of the device does not

require readjustment of the tension means when restored to normal position.

A further object is to provide a very simple construction with a minimum of parts and free of obstructions to the efficient operation of the wringer.

Other objects and advantages will be apparent in the following detailed description of a preferred embodiment of my invention which I have illustrated in the accompanying drawings. It will be understood, however, that in the appended claims I aim to cover all legitimate variations and modifications of the preferred construction illustrated herein, which are within the scope of my invention.

In the drawings, Figure 1 is a side elevation of a wringer equipped with my device.

Fig. 2 is an end view showing the parts in normal position for the operation of the wringer.

Fig. 3 is an end view illustrating the device in position to release the rollers from tension.

Fig. 4 is an end view showing the upper roller lifted and supported free from the lower roller with the releasing arms in extreme position.

Fig. 5 is a partial plan view of the device.

Fig. 6 is a detail plan view of a part of the releasing device.

In the embodiment of my invention herein illustrated, I have shown a wringer as adapted for use in a conventional manner upon a mechanical washing machine. The wringer is mounted upon a swinging bracket 10 which carries a gear box 11 housing a suitable gear mechanism adapted to drive the wringer rolls. The bracket 10 may be provided with a depending tubular extension 12 through which a drive shaft 13 may extend into the gear box for the operation of the gear mechanism. The tubular portion 12 may be adapted for pivotal mounting in a suitable support carried by the washing machine. A hand lever 14 may be provided on the upper portion of the gear box for the convenient operation of means controlling the engagement of the driving mechanism actuating the wringer rolls.

A pair of spaced journal blocks 15 and 16, rising from the upper surface of the bracket

10, carry the ends of the shaft 17 upon which is formed the lower roll 18 of the wringer, and serve as the lower half of the journals for the respective ends of the roller shaft.

8 The shaft 17 has a suitable driving connection at one end with the gear mechanism housed in the gear box 11. Overlying and suitably secured to the journal blocks are a pair of cross members 19 and 20 extending a 10 substantial distance on both sides of the journal blocks and forming at their central portions journal caps 21 securing the journalled ends of the roller shaft 17.

15 Positioned above the cross members 19 and 20, are a pair of swinging bearing supports 22 and 23, pivoted to the ends of the cross members on one side of the wringer, as at 24. The swinging supports 22 and 23 carry suitable bearings for the ends of a 20 shaft 25 upon which an upper roll 26 is constructed. These bearings may comprise in each support a downwardly opening slot 27 in which the shaft end is journalled and secured against displacement therefrom by 25 means of a cross pin 28 inserted through the side walls of the slot beneath the shaft. The bearing slots 27 are so positioned that when the supports 22 and 23 are in normal position, the upper roll lies immediately above 30 the lower roll and in contact therewith. The supports 22 and 23 are adapted to swing upwardly about their pivots and carry the upper roll 26 a substantial distance away from the lower roll 18.

35 Rigidly mounted upon the ends respectively of the upper and lower roll shafts adjacent to the gear box, are a pair of gears 29 and 30 which interengage when the upper roll is in operative position upon the lower roll, and by which the upper roll is operatively driven.

To secure the rolls in normal relation with the necessary compression for the operation of the wringer, I have provided releasable tension means comprising a pair of upright rods 31 and 32 pivoted on the forked ends 33 and 34 of the cross members 19 and 40 20. The rods 31 and 32, rising from the cross members, pass in normal position between the bifurcated ends 35 and 36 of the bearing supports for the upper rolls, and extend upwardly therefrom to the control bar 37 rigidly connecting the two rods.

45 Each of the upright rods is screw-threaded over its portion extending above the bifurcated end of the bearing support, as at 38, and has threaded thereon a hand wheel 39 abutting which is a coiled spring 40 extending downwardly about the rod. The lower end of the spring 40 is confined by a washer 41, limited in its downward movement by a cross pin 42 fixed in the rod. The cross pin 40 60 42 is located so that when the upright rod is in engagement with the bifurcated end of the bearing support in normal position, the

pin is below the upper surface of the bearing support.

The extremities of each of the bifurcated end portions 35 and 36 of the bearing supports, are constructed with an inclined surface approaching the upper surface of the support, and so arranged that when the upright rods are swung into engagement with the ends of the supports, the washers 41 slide over the inclined surfaces, thereby accomplishing the compression of the coiled springs in passing to their normal position at rest upon the upper surface of the bearing supports. When so normally positioned, the upright rods may be slightly inclined inwardly toward the rollers so that the bearing angle of the springs upon the surfaces of the supports is such as to effect a locking position, and prevent the disengagement of the upright rods otherwise than by a positive movement of the control bar.

20 The construction here described provides for the positive securing of the upper roll in operative relation to the lower roll. Any desired degree of compression between the 90 rolls may be secured by varying the tension of the coiled springs through varying the position of the hand wheels 39 upon the upright rods.

25 With the outward swinging of the control 95 bar 37, the tension springs are carried out of engagement with the upper roll bearing supports, instantly releasing the latter and permitting the roll to be swung upwardly away from the lower roll. Releasing the roll, however, does not disturb the adjustment of the spring tension. The stop pins 42 retain the spring adjustment and hold the washers 41 in position for reengagement with the reverse swing of the control bar.

30 The control bar is sufficiently elevated above the rolls to offer no obstruction to the ordinary use of the wringer, and by reason of its location, may be reached by the operator from any position on either side of the wringer. A further advantage is that the control bar extends over the entire length of the rolls. The long bar is conspicuously 105 outstanding and may be grasped or struck to immediately release the rollers in case of accident without searching for a less available operating lever.

35 A further important advantage in my construction resides in the provision of 110 means for positively lifting the upper roll bearing supports after their release. By this means a wide separation between the rollers is positively accomplished, and in case of clothes becoming wound about both rolls, the latter may be forced apart to facilitate removal of the clothes. The positive separation of the rolls also makes possible the quick withdrawal of an operator's 115 hand, which may be caught between the rolls.

- To accomplish these ends I have provided angular extensions 43 and 44 on the upright rods 31 and 32, extending below the cross members 19 and 20, and carrying at their extremities connecting links 45 and 46, the latter being pivoted at 47 and 48 on the upper roll bearing supports 22 and 23. The connections between the extensions 43 and 44 and their respective connecting links include arcuately slotted portions 49 formed at the ends of the links. Pins 50 fixed in the extremities of the extensions 43 and 44 extend through the slots and carry suitable washers at their outer ends to prevent displacement of the links.
- During that portion of the swinging movement of the upright rods 31 and 32 which carries the tension springs out of engagement with the bifurcated ends 35 and 36 of the bearing supports, the pins 50 slide through the arcuate slots without operating the connecting links. As soon as the tension springs have cleared the ends of the bearing supports, the pins 50 engage the ends of the arcuate slots and by continuing the swinging movement of the upright rods, cause the links 45 and 46 to force the bearing supports 22 and 23 upwardly about their pivotal supports upon the cross members 19 and 20. When in extreme outward position the weight of the upright rods and the control bar is sufficient to hold the upper roll in raised position. In the reverse movement of the upright rods for restoration of the rolls to operative position, the bearing arms are first lowered so that the two rolls are again positioned in operative relation, whereupon the cross pins 50 again travel the arcuate slots while the tension springs ride up over the bifurcated ends of the bearing supports to their normal operating positions.
- It will now be apparent that I have provided quick releasing means of very simple and inexpensive construction which securely holds the rolls in proper operating relation, under any desired tension until it may be desired to release them; and that the latter operation may be accomplished by a simple movement of a readily accessible control bar, thereby instantly releasing the rolls and positively forcing their separation. It will also be observed that the raising and lowering of the upper roll and its supports may be controlled entirely by the swinging of the control bar without necessity for separately replacing the rolls after their release.
- I claim as my invention:
1. A wringer comprising a pair of rolls, releasable means adapted to be moved into one position for forcing said rolls together and into another position for separating said rolls, movable means for holding said releasable means in said first position, said movable means when out of holding position permitting separation of the rolls, and a lost motion connection between said releasable means and said movable holding means to permit separating the rolls without motion of the movable means, said movable means and said lost motion connection permitting separation of the rolls positively by moving the holding means.
  2. A wringer comprising a stationary support having a roll journalled therein, a swinging support pivoted on said stationary support and having a second roll journalled therein, means hinged on one of said supports movable to and from the other support, tension means carried by said hinged means operable to effect compression between said rolls, and means operable by said hinged means for positively separating said rolls when said tension means is inoperative.
  3. A wringer comprising a stationary support carrying a roll, a swinging support pivoted on said stationary support and carrying another roll, releasable means for resiliently forcing said swinging support toward said stationary support to effect compression between said rolls, and links between said means and said swinging support operable by said means to move said swinging support to and from said stationary support when released.
  4. A wringer comprising a pair of supports pivotally engaged at one end and adapted to swing relatively to each other, a pair of rolls journalled intermediately of the ends of said supports respectively, means mounted on the opposite end of one of said supports adapted to detachably engage the corresponding end of the other of said supports and resiliently force said supports toward each other, and a link carried by said means and pivotally attached to said other support whereby said other support may be positively swung when its said end is disengaged from said means.
  5. A wringer comprising a lower roll, a stationary journal support therefor, an upper roll, a swinging journal support for said upper roll, said swinging support being pivoted laterally of said rolls upon said stationary support, a bifurcated arm on said swinging support projecting laterally opposite said pivoted portion, a member pivoted on said stationary support and swingable into engagement with said bifurcated arm, a hand wheel having screw threaded engagement with the free end of said member, an intermediate stop fixed on said member inwardly from the point of engagement with said arm, and a spring confined between said hand wheel and said stop, the inward end of said spring riding upon and being tensioned by said arm when said arm and said member are engaged.
  6. A wringer comprising a stationary roll, a movable roll, releasable tension means

operable upon said movable roll for forcing said rolls together, and links connected with said tension means and said movable roll whereby said rolls may be forced apart with the release of said tension means, said links being inoperative while said tension means is in operative position.

7. A wringer comprising a stationary roll support, a movable roll support, a member pivoted on said stationary support and operable to detachably engage said movable support, means carried by said member adapted to force said movable support toward said stationary support when said member and said movable support are in engagement, and a link pivoted on said movable support and having a lost motion connection with said member, said link being inoperative during the movement of said member into and out of engagement with said movable support, and operable by the movement of said member when free of said engagement to swing said movable support to and from said stationary support.

8. A wringer comprising a stationary roll support, a movable roll support, a member pivoted on said stationary support and operable to detachably engage said movable support, means carried by said member adapted to force said movable support toward said stationary support when said member and said movable support are in engagement, a link having one end pivotally connected to said movable support, the other end of said link having a slot therein, and a pin fixed on said member having engagement within said slot, the pin engaging the end of said slot to raise the arm, said pin and slotted

end of said link permitting relative movement therebetween freely except when said member is disengaged from said movable support.

9. In a wringer, a stationary bearing support, a movable bearing support having a hinged connection therewith, a bifurcated arm projecting from said movable support oppositely to said hinged connection, said arm having an inclined end, a rod pivoted on said stationary support operable to engage said bifurcated arm, a spring coiled about said rod, an adjustable tensioning abutment for said spring carried on the free end of said rod, and a fixed abutment on said rod near the pivoted end thereof, said fixed abutment being located to position the adjacent end of said spring so that with the movement of said rod into engagement with said bifurcated arm said inclined end will engage and compress said spring free from said fixed abutment.

10. A wringer comprising a lower roll, stationary end bearings for said roll, an upper roll, movable end bearings for said upper roll, a pair of members pivoted respectively to each of said stationary bearings, tension means carried by each of said members operable to force said movable bearings toward said stationary bearings, said means being releasable by the swinging of said members, and a bar extending between said members operable to swing said members simultaneously.

In testimony whereof, I have hereunto set my hand.

FRANK B. ZIEG.
